[57] ABSTRACT

The disclosure of the invention is directed to an improvement in the developing mechanism for duplicating sheets of heat sensitive latent image bearing microfilm. The microfilm sheets are copied by exposing film from a roll through a master microfilm sheet, cutting the exposed film from the roll and developing the film in a heating chamber. The heating chamber contains thermostatically controlled heating elements to maintain the temperature at substantially 285°-290° Fahrenheit for a dwell time of 5 - 7 seconds. The film is continuously moved through the heating chamber by a roller conveyor providing a continuously moving and changing contact area with the film on an emulsionless surface. The film is transferred to a belt conveyor having end rollers no larger in diameter than the rollers in the roller conveyor but having a flat surface to provide cooling for the developed sheets before being delivered to a collection point in the mechanism.

FIG. 3.

DEVELOPING MECHANISM FOR MICROFILM

This invention is directed to a microfilm duplicating mechanism and more particularly to the means for developing the exposed microfilm which is heat sensitive and includes a latent image.

In the duplication process of duplicating microfilm which has a heat sensitive latent image it has been found that some of these films require a developing time of approximately 5 to 7 seconds in a heating chamber forming the developer which renders the plastic material forming the film substrate to become very soft and pliable preventing any form of pressure contact with the emulsion side of the film. Some films are made with a rapid developing time so that heat may be applied to the film and the film passed through pinch rollers to conduct the film through the developer without having the emulsion separate from the film substrate. However, for the film first described above, any attempt to pass the film continuously through pinch rollers causes the emulsion to be transferred to the pinch rollers and thus ruin the new film sheet.

Because the film does become very pliable, it is necessary to move the film in such a manner that there is little contact with the conveying mechanism in order to prevent hot or burned spots on the film such as may be encountered where a flat belt type conveyor may be used to convey the film through the heat chamber. It is also necessary to remove the film from the developer and cause it to cool on a flat surface so that the film sheet remains flat and does not incur a permanent "set" to the film from any "sag" which may be imparted through the use of a continuously moving contact member with the film.

It is therefore a general object of this invention to provide an improved developer of heat sensitive latent image bearing microfilm.

It is still a further object of this invention to provide a developer of heat sensitive latent image bearing microfilm in which the exposed film is moved through the developer having continuously moving and changing contact areas engaging the film.

It is still a further object of this invention to provide means for moving film through a developer by engaging the emulsionless surfaces of the film to be cured by heat.

It is yet another object of this invention to provide a roller conveyor means to transport the heat sensitive latent image bearing microfilm through the developer.

It is still another object of this invention to provide means for developing heat sensitive latent image bearing microfilm at a temperature range of 285°-290° Fahrenheit while conveying the same through the developer with a dwell time of 5 - 7 seconds.

These and other objects and advantages of the invention will more fully appear from the following description, made in connection with the accompanying drawings, wherein like reference characters refer to the same or similar parts throughout the several views, and in which:

FIG. 1 is a diagrammatic view of the invention showing the mechanism for exposing and developing heat sensitive latent image bearing microfilm;

FIG. 2 is an elevational side view of the heat chamber and conveyor mechanism from the developer mechanism; and

FIG. 3 is an electrical schematic showing the electrical circuit controlling the duplicating mechanism.

By reference to the Figures, and particularly FIG. 1 where a roll of film 10 is suspended upon a spindle 11, it is drawn between an alignment spool 12 to pass over a film holder 13. Film holder 13 carries a master film 14 which is to be copied. A cover plate 15 is hingedly supported at its rear through suitable means so that it may be drawn down tightly upon holder member 13 and thus hold film 10 in contact with the master 14. A mask 16 below film holder 13 works in conjunction with a shutter mechanism 17 which has an elongated slot 20 formed in the center of a half section of a cylindrical member which has a lamp 21 in the form of an ultraviolet light that causes its rays to be emitted upwardly through the master film to be copied to expose film 10. Shutter member 17 rotates through 180° to block the light from being transmitted through mask 16, permitting light to pass through slot 20 and again block the light from passing mask 16. The rate at which shutter member 17 is oscillated provides an adjustment for the developing time. The shield 17 is pivoted about an axis 22 which permits the 180° movement of the shutter member 17.

After the film has been exposed, the pressure is released from cover 15 and film 10 is advanced by a pair of rollers 23 and 24 which are driven by a motor mechanism to cause an advancement of film 10 one length of the master film 14. The film is then stopped and a knife mechanism 25 is energized which cuts the film the proper length. Film 10 is then advanced through a pair of curved guide members 26 and 27 until it reaches another pair of rollers 30 and 31, one of which is driven by a motor and the other which may be a pinch roller to further guide and move film member 10 through an intermediate pair of guide members 32 and 33 which causes the film sheet 10 to be moved vertically between guides 32 and 33.

Another pair of rollers 34 and 35, one of which is a pinch roller and the other of which is driven through a chain drive connected to the driving motor, causes film 10 to be engaged and propelled downwardly between another pair of curved guide members 36 and 37. Guide members 36 and 37 cooperate to change the course of film sheet 10 from a vertical downward movement to one which is substantially horizontal. Film sheet 10 is then engaged by another pair of rollers 40 and 41 where roller 40 is in the form of a pinch roller and roller 41 is a driven roller, the driving mechanism being a constant speed motor. A plurality of rollers 42 through 50 are disposed to form a roller conveyor and conduct film sheet 10 across the rollers on the emulsionless side of the film.

Rollers 40 through 50 are contained within a heating chamber 60 which is shown in more detail in FIG. 2 and which contains four heating elements 61 through 64.

After the film has been developed in the heating chamber 60, a belt conveyor 70 receives the developed film 10. Conveyor 70 has a roller 71 over which the belt is rotated, roller 71 being disposed adjacent roller 50 of the roller conveyor and having a diameter no larger than roller 50 to cause a minimum amount of "droop" of the film in transferring from the roller conveyor to the belt conveyor. Another roller 72 rotatably secures the belt in place at the end of the conveyor and film sheet 10 is then retained by a collector box 80 at the end of conveyor 70. A cover plate 81 is formed about conveyor 70 to direct any of the air currents used generally to cool lamp 21 from reaching the film sheets 10

and disturbing them during their cooling period in moving from the developer to the collector box 80.

For a more complete disclosure of the exposure mechanism and that portion of the duplicating device before reaching the developer in the form of the heating chamber 60 and conveyor 70, reference may be had to a co-pending application entitled "Microfilm Duplicating Device" and assigned to the same Assignee.

Developer 60 is in the form of a metal enclosure 65 which has an inlet opening 66 and an outlet opening 67 through which film 10 enters and is discharged. A metal barrier 68 is secured between the floor of the box 65 and below roller members 41 through 50. Heating elements 61 through 64 are contained with a cavity 69 formed between barrier 68 and the sides and bottom of box 65. A thermostat 73 is disposed on the upper outside portion of heating chamber 60 and is used to control the electrical connections to heating elements 61 and 62 as shown schematically in FIG. 3.

A drive sprocket 51 is rotatably secured to case 65 and has seven idler sprockets 52, 53, 54, 55, 56, 57, and 58 rotatably secured to housing 65 in cooperation with a chain 59 which engages sprocket teeth found on each of rollers 41 through 50. Sprocket 51 is rotated in such a manner as to cause rollers 41 through 50 to produce a movement of film sheet 10 from opening 66 through opening 67 in the heating chamber 60. Sprocket 51 is connected to a motor 74 through suitable means such as a shaft 75. It may also be desirable to paint the inside of cavity 69 so that a more uniform radiator is formed by barrier 68. Additionally, a conveyor motor 76 is connected to driving roller 71 through suitable means such as a shaft 77. Motors 74 and 76 are generally constant speed motors and operate with appropriate gear reductions so that a sheet of microfilm approximately 4 inches by 5 inches in size may be conveyed through developer 60 in approximately 5 to 7 seconds. It was found that roller 71 should be of a diameter no larger than the size of rollers 41 through 50 so that the film may be transferred to conveyor 70 without appreciable distortion and upon cooling on conveyor 70, the film will remain in a flat condition.

Plate 81 may be eliminated if cooling currents of air are not admitted to the area in which the film is conveyed on conveyor 70, it being understood that the film must lie flat on the conveyor in order to produce a flat sheet before reaching the collection point 80 at the end of conveyor 70.

It has also been found that cavity 69 is heated to the correct temperature of 285° to 290° Fahrenheit by applying current to heaters 63 and 64 continuously, the heaters being approximately 200 Watts each. The incremental control needed to keep the temperature variation within the limits just described is achieved with heaters 61 and 62 which are connected in series with each other through the use of a thermostat 73, heaters 61 and 62 being of 50 Watt ratings.

OPERATION

The control circuit is shown in FIG. 3 in simplified form showing the mechanical structure as controlled by the electrical circuit. To better understand the circuit, the lines appearing between a pair of power lines 90 and 91 are labeled at the left, line numbers designating the particular electrical circuits which will be used to identify the components therein. Alternating current of

110 volts 60 cycles is applied to lines 90 and 91 through a master switch 92 which applies current through a fuse 93 and energizes a lamp 94 indicating that the equipment is ready to start developing. It will of course be understood that a lamp switch 95 will also be closed applying current to ultraviolet lamp 21 which is shown diagrammatically in FIG. 1. After an appropriate warm-up period, and with a master 14 in film carrier 13, a print switch 96 is momentarily closed which causes a control relay CR2 in line 2 to be energized and which in turn closes relay contacts CR2 in line 2 thus forming a holding circuit. Connected in parallel with control relay CR2, is a timed relay TR3 which closes its contacts up to 1 second later, closing contacts TR3 in line 4. A shutter drive cam 100 in its at rest position, closes a switch 101 in line 4 thus applying current to timed relay TR4 which applies a pulse for a fraction of a second to a cam solenoid 102. The duplicating mechanism uses a number of motors, several of which are connected to the mechanical drive through the means of a mechanically engaged clutch. The clutches are spring loaded and have a cam or collar control member held against rotation through a detent actuated by a solenoid. Upon release for rotation the clutch may rotate the cam 180° or 360° depending on the number of detents. A clutch 103 is actuated by solenoid 102, and a motor 104 provides a rotational drive for the clutch. Clutch 103 drives a cam 105 to cause cover 15 to be secured against film carrier 13 and also drives a cam 106 which is used to actuate a switch 107 and cause switch 107 to engage the contact on line 10.

Current is also applied to timed relay TR5 in line 5, and contacts TR5 are closed applying current through switch 107 to a shutter solenoid 110. A clutch 111 is mechanically connected to solenoid 110 and is also mechanically connected to a variable speed motor 112 which causes a rotation of shutter 17 and switch cam 100. After cam 100 rotates, the contacts of switch 101 are broken and the circuit is broken to relays TR4 and TR5 which opens the circuit to the shutter solenoid 110. After the shutter has contained its 180° movement through an eccentric arm, it comes to rest with the light from lamp 20 being blocked from entry to the film carrier and master film 14. However, when cam 100 rotates 180°, switch 101 is again actuated momentarily which again energizes relays TR4 and TR5 to cause cams 105 and 106 to be rotated. While switch 107 is closed to provide current to shutter solenoid 110, the shutter continues to move to its closed position 180° from that which it first started. In the meantime, the cover 15 has been moved upwardly to clear film 10 and allow it to be drawn through between the cover 15 and holder 13.

Switch 107 now engages its contact in line 9, applying current to a metering roll solenoid 113. A clutch 114 is engaged by solenoid 113 and mechanically connects a drive motor 115 through an output shaft which is connected to drive roller 24 and a switch cam 116. Roller 24 is mechanically connected to the other drive rollers 30, and 34 which produce movement of the film through the guide members. As film 10 is advanced by motor 115 and metering roll 24, cam 116 permits a switch 117 in line 9 to engage another set of contacts, connecting it directly to a control relay CR6 in line 6. A holding circuit is created in line 6 through a pair of normally open contacts CR6.

After 360° of travel of cam 116, switch 117 is again connected with the line energizing timed relay TR7 through control relay contact CR6 in line 8. Timed relay TR7 has two forms of delay, one of which occurs while the relay coils are energized and the other delay follows de-energization of the coils for a period of time before returning the circuit to the condition shown in FIG. 3. Line 7 forms the holding circuit during the "on" delay and at the end of the "off" delay, relay TR7 is returned to the condition shown in the drawing. Upon energizing timed relay TR7, the normally closed contacts in line 1 are open, thus breaking the circuit to CR2, TR3, TR4, TR5, and CR6. In other words, the film has been advanced a length of the master film and the sequence is ready to be repeated. Through the use of a cut switch 120, in line 12, a solenoid 121 is actuated which is directly connected to knife 25 to sever the film at that point.

It may be desirable to adjust the speed of the shutter motor and this may be accomplished through the use of a mechanism such as the Dayton Triac Control, No. 4X796 which is an SCR control for use with motor 112 and is designated as a speed control 122.

As explained briefly before, heat is maintained in the heating chamber through the use of heaters 63 and 64 and the heat variation is maintained and controlled through the use of series heaters 61 and 62 controlled by thermostat 73.

The developer motor 74 drives the roller conveyor within the developer causing the sheet film to be delivered to conveyor 70 which is driven by motor 76.

It will of course be understood that mechanism may be operated in an automatic mode and that numerous copies may be made by the use of a counter. The disclosure of such a mechanism is found in the co-pending application mentioned previously.

It will, of course, be understood that various changes may be made in the form, details, arrangement and proportions of the parts without departing from the scope of the invention which consists of the matter shown and described herein and set forth in the appended claims.

What is claimed is:

1. An improvement in a duplicating mechanism for heat sensitive latent image bearing microfilm having a film holder for holding such microfilm to be duplicated with a film exposure device disposed in operable position in spaced and confronting relationship therewith, said film exposure device cooperating with means for supplying film to be exposed to the film exposure device and having a cutter operably disposed and controlled to deliver selected lengths of exposed microfilm from said film exposure device, said improvement comprising:

a. a heating chamber having inlet and outlet openings formed therein admitting and discharging said selected lengths of microfilm, said chamber including a plurality of heating elements disposed generally opposite the emulsion surface of such selected lengths of exposed microfilm;

b. film transporting means constructed and arranged within said heating chamber between said inlet and outlet openings and having continuously moving and changing contact areas engaging a substantially emulsionless surface of such selected lengths of microfilm, said transport means operating at a speed permitting the latent image in such film to be fully developed;

c. and a conveyor mechanism communicating with said film transporting means and said outlet opening of said heating chamber having a flat support thereunder conveying such developed film to a collection point, said conveyor mechanism conveying such film in a flat condition until the film emulsion is set and the latent image is fixed therein.

2. The structure set forth in claim 1 wherein said heating chamber includes:

thermostatic control means connected to less than the total of said plurality of heating elements providing incremental changes in heat variations within said heating chamber.

3. The structure set forth in claim 1 wherein said inlet and outlet openings in said heating chamber are substantially in horizontal opposition to each other.

4. The structure set forth in claim 1 wherein said film transporting means includes roller conveyor means constructed and arranged to convey such selected lengths of film in substantially a horizontal manner.

5. The structure set forth in claim 4 wherein said conveyor mechanism includes an endless belt conveyor having at least a pair of rollers at each end thereof, the end communicating with said film transporting means having a roller no larger in diameter than the rollers in said roller conveyor means.

6. The structure set forth in claim 1 wherein said heating chamber maintains a temperature range between 285° and 290° Fahrenheit.

7. The structure set forth in claim 6 wherein said film transporting means moves such selected lengths of microfilm through said heating chamber in substantially 5 - 7 seconds.

8. The structure set forth in claim 2 wherein said heating chamber includes:

a cavity containing said plurality of heating elements, said cavity being disposed beneath said film transporting means.

9. The structure set forth in claim 4 wherein said film transporting means includes:

a pair of rollers including a pinch roller disposed adjacent said inlet opening between which such selected lengths of exposed microfilm are engaged and moved onto said roller conveyor means before being exposed to the heat from said heating chamber.

10. An improvement in a developer of heat sensitive image bearing microfilm comprising:

a. a heating chamber having inlet and outlet openings formed therein admitting and discharging respectively selected lengths of exposed and developed microfilm, said chamber including a plurality of heating elements disposed generally opposite the emulsion surface of such selected lengths of exposed microfilm;

b. film transporting means constructed and arranged within said heating chamber between said inlet and outlet openings and having continuously moving and changing contact areas engaging a substantially emulsionless surface of such selected lengths of microfilm, said transporting means operating at a speed permitting the latent image in such film to be fully developed;

c. and a conveyor mechanism communicating with said film transporting means and said outlet opening of said heating chamber having a flat support thereunder conveying such developed film to a col-

lection point, said conveyor mechanism conveying such film in a flat condition until the film emulsion is set and the latent image is fixed therein.

11. The structure set forth in claim 10 wherein said inlet and outlet openings in said heating chamber are substantially in horizontal opposition to each other and said film transporting means includes roller conveyor means constructed and arranged to convey such selected lengths of film in substantially a horizontal man-

ner.

12. The structure set forth in claim 10 wherein said heating chamber maintains a temperature range between 285 and 290 degrees Fahrenheit and said film transporting means moves such selected lengths of microfilm through said heating chamber in substantially 5 - 7 seconds.
